WILLIAM FAIRLEY
By Victor J. Evans
Attorney.*

UNITED STATES PATENT OFFICE.

WILLIAM FAIRLEY, OF OAKLAND, CALIFORNIA.

WINDOW CONSTRUCTION.

Application filed September 24, 1926. Serial No. 137,575.

This invention relates to improvements in windows, and has particular reference to a hinged window construction.

The principal object of this invention is to provide means whereby the ordinary vertically raising and lowering sashes may be swung inwardly or outwardly so as to take a position within the room for the purpose of ventilation, or for a cleaning of the window panes.

Another object is to provide a device of this character which is simple in construction, and therefore cheap to manufacture.

A further object is to provide means whereby one or more of the sashes may be swung independent of the other.

A further object is to provide a device of this character which may be employed either in old or new building construction.

Other objects and advantages will be apparent during the course of the following description.

In the accompanying drawings forming a part of this specification, and in which like numerals are employed to designate like parts throughout the same,

Figure 1 is a front elevation of a window constructed in accordance with my invention, and partly broken away in order to better illustrate the same,

Figure 2 is a cross-section taken on the line 2—2 of Figure 1,

Figure 3 is a cross-section taken on the line 3—3 of Figure 1,

Figure 4 is a view similar to Figure 3 showing one of the sashes in a partly opened position,

Figure 5 is an enlarged fragmentary detail view showing the hinge construction,

Figure 6 is a view similar to Figure 5 showing the sashes swung to open position,

Figure 7 is a detail perspective view showing the manner in which the hinges are positioned upon the supporting rods,

Figure 8 is a perspective view of one of the securing brackets, and

Figure 9 is a perspective view of one of the hinge members.

At the present time it is not possible to swing a sliding sash out of its normal path of movement, as for instance, into the room. I have therefore devised a hinge whereby the sliding sashes may be individually swung into the room either for the purpose of cleaning or for the purpose of ventilation, and further I produce a window structure where-

in the effect of French doors may be gained.

In the accompanying drawings wherein for the purpose of illustration is shown a preferred embodiment of my invention, the numeral 5 designates a window frame in which sashes 6 and 7 are positioned, the sash 6 being the upper sash and the sash 7 the lower sash.

At 8, I have shown the customary weight box in which weights 9 move. These weights are attached by means of cables 11 to their respective sashes 6 and 7.

Extending between the top and bottom of the window frame are rods 12 and 13. Upon these rods 12 and 13 the sashes 6 and 7 respectively are adapted to slide. The sash 6 has secured thereto spaced hinge plates 14 which carry pintles 16, to which pintles are pivoted hinge plates 17, which hinge plates in turn engage the rod 12 and are slidable thereon (see Figure 7).

It is obvious that the weight of the sash would cause the rod 12 to bend, and in order to strengthen the same, I place parallel thereto an auxiliary rod 18 which is secured to the frame 5 as by screw eyes 19 and 21.

A slider 22 is positioned upon the rods 12 and 18 and lies between the hinge plates 17. The rods 12 and 13 are secured to the frame 5 as by brackets 23 and 24. The sash 7 is mounted in a similar manner with the exception that the hinge plate corresponding to the hinge plate 17 of the sash 6, is formed with a right angle bend therein as shown in Figure 9. This hinge plate is designated by the numeral 26, while its co-acting hinge plate 27 is shown in Figure 5 as being connected to the sash 7. A roller 28 is secured to the sash 7 and engages a molding 29 hingedly secured to the frame 5.

The result is that a window constructed in accordance with my invention may be operated as follows:—

Assuming that the window is closed as shown in Figure 1, and it is desired to open the sash 7, the same may be elevated in the ordinary manner at which time the hinge plates 26 will slide upon the rod 13. As the lower hinge member contacts the slideable member 22, the same will be moved upwardly together with the sash thereby maintaining the proper bracing of the rod 13 as the weight of the sash moves thereover.

Should it be desired to swing the sash vertically, the sash is first moved upwardly until the roller 28 passes the upper extrem-

ity of the molding, after which the molding 29 may be moved to its full line position of Figure 4.

The window may then be swung upon the 5 rod 13 as indicated in Figure 4, after which the upper sash 6 may be moved downwardly and swung upon its rod 12.

Should it be desired to swing both windows so that they will lie parallel, or in the 10 position shown in Figure 6; further movement of the sash 7 will cause the window to swing upon the rod 13 as well as the pintle 16 which will bring the window to a point beyond the line of the window frame, after 15 which the sash 6 may be moved to its position of Figure 6.

It will thus be seen that I have provided a simple construction which will accomplish all the objects above set forth.

20 It is to be understood that the form of my invention herewith shown and described is to be taken as a preferred example of the same and that various changes in the material, shape, size and arrangement of parts 25 may be resorted to without departing from the spirit of the invention or the scope of the subjoined claims.

Having thus described my invention, I claim:—

30 1. In a device of the character described, the combination with a window frame having a pair of sliding sashes positioned therein, a rod positioned adjacent each of said sashes, hinge connections extending between each of said rods and their respective sashes,

an auxiliary rod mounted parallel with each of said rods, a slider connecting said rods and their respective auxiliary rods, for the purpose specified.

2. In a device of the character described, 40 the combination with a window frame having a pair of sliding sashes positioned therein, a rod positioned adjacent each of said sashes, hinge connections extending between each of said rods and their respective sashes, 45 an auxiliary rod mounted parallel with each of said rods, a slider connecting said rods and their respective auxiliary rods, said slider being positioned between the hinge connections of each of said sashes and their 50 respective rods.

3. In a device of the character described, the combination with a window frame having a pair of sliding sashes positioned therein, a rod positioned adjacent each of said sashes and extending to the top from the bottom of said window frame, spaced hinge plates secured to each of said sashes, pivoted hinge plates secured to said first mentioned hinge plates, said second mentioned hinge 60 plates being adapted to engage and slide on their respective rods, an auxiliary rod positioned parallel to each of said first mentioned rods, a slider connecting said rods and their auxiliary rods, said slider being positioned between the hinge connections of each of said sashes and their respective rods.

In testimony whereof I affix my signature.

WILLIAM FAIRLEY.
